UNITED STATES PATENT OFFICE.

ALBERT EICHHORN AND JESSE EICHHORN, OF CAMDEN, NEW JERSEY.

BLANK FOR COLLAPSIBLE BOXES.

1,125,987.

Specification of Letters Patent.

Patented Jan. 26, 1915.

Application filed December 1, 1909. Serial No. 530,306.

To all whom it may concern:

Be it known that we, ALBERT EICHHORN and JESSE EICHHORN, citizens of the United States, residents of Camden, in the county of Camden, State of New Jersey, have invented a new and useful Blank for Collapsible Boxes, of which the following is a specification.

Our invention relates to improvements in collapsible or folding boxes.

The object of our invention is to provide an improved collapsible or folding box preferably made from a blank stamped or cut from a single sheet of card board, or other suitable material.

Our improved box is adapted for packing and shipping merchandise and also for displaying the same.

The box is made preferably from a blank stamped from a single sheet, the end and sides being properly creased so as to be formed into a box and lid therefor, wings and coöperating slits being provided as disengageable means for holding the parts in operative relationship. The lid is preferably hinged to the box with a double hinge. The lid has inclined sides so that when it is folded under the box, it serves to support the box at a suitable inclination for displaying the contents thereof.

Referring to the drawings:—Figure 1 is a plan view of the blank from which the box is formed. Fig. 2 is a perspective view of the box with the lid closing the same. Fig. 3 is a similar view with the box open and the lid supporting the same in the display position.

Similar numerals refer to similar parts throughout the several views.

The blank is so formed as to provide the bottom and top portions 20 and 22, the flanking members or sides and ends of the box, 4 and 5 and 6 and 7, and also the several flanking members of the lid hereinafter described. The end portion 6 is provided with the wings 8 and 9 having hooks 10 and 11 at their free ends, while end portion 7 has similar wings 12 and 13 with the hooks 14 and 15 at their free ends. The side portions 4 and 5 are provided with the diagonal slits 16, 17, 18 and 19 for engaging the hooks 10, 11, 14 and 15 respectively, when the side portions 4 and 5 and end portions 6 and 7 are bent into planes at right angles with the bottom portion 20, and the wings 8,

9, 12 and 13 are bent around to overlap the sides 4 and 5 as clearly shown in Fig. 3.

Connected with the end portion 7 is the lid connecting portion or member 21, which is joined to the top portion 22 of the lid.

The side portions 23 and 24 of the lid are wedge shaped, that is, have inclined margins, as clearly shown in the drawings. These side portions 23 and 24 are provided with the slits 25 and 26 respectively. The end portion 27 is provided with the wings 28 and 30, having the hooks 29 and 31 for engaging with slits 25 and 26 respectively, when the sides 23 and 24 and end 27 are folded in planes at right angles with the top 70 22 and the wings 28 and 30 are folded about and overlap the sides 23 and 26 respectively.

As a preferred construction of our box we provide reinforcing strips 32 and 33 at the creases which form the double hinge connection between the lid and box.

Fig. 2 shows the box assembled or made up, that is with the parts in operative relationship, and with the lid closing the same, while Fig. 3 shows the box assembled, but 80 in the open position, resting in an inclined position upon the lid for displaying the contents.

It will be obvious that a box made in accordance with our invention, as above described, will possess many advantages. For example, such a box can be made very cheaply. It can be shipped in large quantities, packed flat, that is, unfolded with all the parts lying in a single plane, so that a large number of boxes can be shipped in a very small package to the place where they are to be used for packaging goods. This not only saves great expense and inconvenience in shipping large quantities of empty boxes, but thoroughly protects them from injury in transportation. When the boxes are delivered where they are to receive the merchandise they are folded and locked with the parts in operative relationship, and the goods are then packed therein. When the box with the contents reaches the retailer, the lid is simply folded back under the box as shown in Fig. 3, and the goods displayed therein until sold. When the contents of boxes are sold, the boxes, as they become empty may be unfolded, into their original sheets or blanks, and packed away in the least possible space, or shipped back for a new supply of merchandise. It will thus be 110

obvious that, when not in use as containers, the convenience and safety in storing or transporting the unfolded blank, add greatly to the utility of such a device

5 What we claim is:—

As an article of manufacture, a blank for a collapsible box, comprising in its longitudinal extension, top, bottom and end sections, also side sections projecting from the

10 top and bottom sections, the side sections of the top having outer longitudinally extending inclined margins, said blank provided with creases between adjacent sections to form hinged relationship therebetween, the

top section comprising in its extension, a 15 connecting portion or panel between creases, said connecting portion or panel corresponding in dimension approximately with the adjacent end section, said blank also comprising within its contour, tongue and recess 20 means for engagement between end sections and side sections.

ALBERT EICHHORN.
JESSE EICHHORN.
